UNITED STATES PATENT OFFICE.

OLIVER WILSON, OF ST. EDWARD, NEBRASKA.

PIPE AND ROD LIFTING TONGS.

No. 889,078.

Specification of Letters Patent.

Patented May 26, 1908.

Application filed January 31, 1908. Serial No. 413,507.

To all whom it may concern:

Be it known that I, OLIVER WILSON, a citizen of the United States, and a resident of St. Edward, in the county of Boone and State of Nebraska, have invented a new and Improved Pipe and Rod Lifting Tongs, of which the following is a full, clear, and exact description.

This invention relates to means for extracting or inserting lining tubes in the bores of oil wells or deep water wells; and has for its object to provide novel features of construction for lifting tongs, which afford a reliable and convenient device, that will without injury thereto, firmly grip the body of a pipe or tube, and that may be connected readily with the usual tackle for raising a tube from or lowering the same in a well bore, as occasion may require; and furthermore to provide lifting tongs, that may be utilized as a means for gripping heavy shafts or rods which are to be raised or lowered, and with suitable hoisting means effect the transfer of such material in a safe and convenient manner.

The invention consists in the novel construction and combination of parts, as is hereinafter described and defined in the appended claims.

Reference is to be had to the accompanying drawings forming a part of this specification, in which similar characters of reference indicate corresponding parts in all the views.

Figure 1 is a side view of the improved tongs, adjusted for receiving a pipe or tube, indicated in dotted lines; Fig. 2 is a side view of the tongs, taken oppositely from that shown in Fig. 1, and representing parts thereof adjusted for gripping a tube or rod shown in dotted lines; Fig. 3 is an enlarged transverse sectional view of the improvement, substantially on the line 3—3 in Fig. 2; Fig. 4 is an enlarged partly sectional side view of a detail of the invention, and Fig. 5 is a transverse sectional view of parts, taken substantially on the line 5—5 in Fig. 4.

Two similar lever bars 10, 10 are main elements of the invention, each comprising a flat bar of suitable metal, said bars being lapped upon each other and pivoted together by a bolt *a*, at a point somewhat near like ends *b* which are lowermost in service.

Upon each of the ends *b* a jaw 10^a is formed and projects at an angle therefrom, these similar jaws having their adjacent side edges

c rendered parallel with each other from their points of junction with the lever bars 10 to the outer ends thereof. A scallop or concave recess *d* is formed in each edge *c*, 60 said recesses of an equal size being disposed oppositely, as is shown in Fig. 3. The parallel side edges *c* of the jaws 10^a may also have serrations *c'* formed thereon, as also appears in Fig. 3. The normally upper ends 65 *e* of the lever bars 10, which are equally distant from the pivot bolt *a*, are laterally perforated, as at *e'*, and in each perforation an oblong link 11 is loosely secured by one end thereof, as indicated in Figs. 1 and 2. 70

The links 11 are of equal length, and at their remaining ends are loosely secured to a coupling ring 12, that is in service engaged by a hook 13 on the pendent chain 14, that is shown broken away but in complete condition is extended to a suitable lifting device, not shown.

A tripping link is employed for control of the lever bars 10 and, as shown, consists of two main portions 15, which are hinged together at one end of each portion, said hinge *g* being preferably in the form of a rule joint having an eye-bolt *h* for a pivot, the eye thereof projecting at one side, as is shown in Figs. 1, 2 and 4. 85

Each link portion 15 is longitudinally recessed from a point near the hinge joint to its other end, and in these rectangular recesses *i*, *i* two similar extension members 15^a are fitted and secured. 90

One extension member 15^a may be rigidly secured in place by rivets *m*, as shown at the right-hand end of the tripping link in Fig. 4; but preferably the other extension member 15^a at the left is rendered adjustable lengthwise by forming a plurality of transverse perforations *n* therein, that may be individually located opposite a similar perforation in the side walls of the recess *i* and thus be adapted for receiving a clamping bolt *o* which, when in place, may be secured by screwing a nut *o'* on its threaded end, and hold the extension member projected a desired extent from the main portion 15, as is shown in Figs. 4 and 5. 95

The outer end of one of the extension members 15^a is longitudinally slotted, as shown at *r* in Fig. 4, and the outer end of the other extension member 15^a is perforated at intervals, as shown at *r'* in Fig. 4, and said ends are pivoted through said slot *r* and said perforations *r'*, flat upon the lever bars 10, at a suitable distance above the pivot bolt *a*, 110

which connection permits the main portion of the tripping link to flex downward if pressure is applied to the hinge or rule joint *g*.

Upon the eye of the pivot bolt *h* one end of a tripping chain or rope 16 is secured, and thence may be extended to a lower point, preferably passing through a ring *p* that is loosely secured upon one of the lever bars 10 near the point of its pivotal connection with the other lever bar, as represented in Fig. 2.

The point of location and length of the members 15, 15^a, comprising the tripping link, will limit the degree of divergence had by the jaws 10^a, so that they may be spaced apart a suitable distance and retained in their diverged condition for receiving between their recessed edges the cylindrical body of a shaft, piston rod, or a well tube, as the case may be.

20 In use as a means for raising or lowering a tube *A*, it is to be understood that the chain 14 is a pendent portion of the usual rigging or tackle employed therefor, so that the improved tongs will be suspended in a proper position for engagement with one or more sections of a well tube *A* that is to be raised or lowered.

It will be seen that if the jaws 10^a are diverged to their limit, and so retained by the tripping link, that is arranged as shown in Fig. 1, the tube *A* may be engaged therewith by inserting it endwise between the jaws, or the upright tube may receive the tongs at the upper end thereof, to adapt the jaws 10^a for gripping a pipe or rod whereon they are mounted, the link members 15 are flexed at their joint by a pull on the chain, then if the tongs are raised by the tackle, the jaws 10^a will grip the tube between the recesses *d*, and hold said tube firmly without marring its surface, so that the tube may be disposed vertically and lowered down into a well bore. In a like manner, a tube that is to be withdrawn from a well bore may be gripped by 45 the improved tongs, and upon applying draft strain the tongs will firmly hold the tube until it is to be released therefrom.

It is evident that the improvement may also be utilized for grabbing other articles than such as are cylindrical, as the jaws 10^a may be applied upon structural beams of different shapes, and detachably secure such beams upon a lifting tackle for handling such material during the work of erecting a structure it is to be made a portion of, and to this end the serrations *c* serve to insure a tight grip of the jaws 10^a thereupon.

Having thus described my invention, I claim as new and desire to secure by Letters 60 Patent:

1. A pipe or rod lifting tongs, embodying two flat metal lever bars lapped upon each

other and pivoted together where they are lapped, said pivot being nearer the lower ends of the bars, a jaw projected laterally from the lower end of each lever bar and scalloped in opposed edges, means for the elevation and support of the tongs, a tripping link that is formed of two extensible sections pivoted together at adjacent ends, and means for downwardly flexing said link.

2. A pipe or rod lifting tongs, embodying two flat metal lever bars of similar form, said bars being lapped upon each other and pivoted where they are lapped, the pivot being nearer one end of the bars than the other, an integral jaw projected laterally from a corresponding end of each lever bar, and having the opposite edges thereof substantially parallel with each other and having opposite scallops in said edges, and a tripping link formed in two sections, a rule joint connecting corresponding ends thereof, outer ends of the link sections being respectively slotted and perforated, and pivots connecting said outer ends with the respective lever bars above their pivoted connection.

3. In a device of the character described, the tripping link, comprising two main sections, a rule joint connection between adjacent ends of said sections, the bodies of said sections being recessed, and an extension member adjustably secured in the recess of a respective section, the outer ends of the extension members respectively having a slot 95 and spaced perforations therein.

4. A pipe or rod lifting tongs, embodying two flat lever bars of similar form, said bars being lapped upon each other between their ends, and pivoted together where they are lapped, said pivot being nearer one end of the lever bars than the other, an integral jaw projected laterally from a corresponding end of each lever bar, the opposite edges of said jaws being substantially parallel with each other, said edges, near their centers, having oppositely scalloped recesses therein and also having serrations in portions outside of the recesses, a tripping link pivoted by its ends upon the respective lever bars above the pivot connection of the latter, said link embodying two main sections, a downwardly flexing rule joint connection joining adjacent ends of the link sections, said joint having an eye-bolt for a pivot, and a flexible connection 115 extending from the rule joint downward.

In testimony whereof I have signed my name to this specification in the presence of two subscribing witnesses.

OLIVER WILSON
